UNITED STATES PATENT OFFICE.

WILLIAM H. BOSER, OF MINNEAPOLIS, MINNESOTA.

PLATEN-PRESS GAGE.

1,383,829.

Specification of Letters Patent. Patented Mar. 16, 1920.

Application filed January 30, 1919. Serial No. 273,989.

To all whom it may concern:

Be it known that I, WILLIAM H. BOSER, a citizen of the United States, residing at Minneapolis, in the county of Hennepin and 5 State of Minnesota, have invented certain new and useful Improvements in Platen-Press Gages; and I do hereby declare the following to be a full, clear, and exact description of the invention, such as will enable others skilled in the art to which it 10 appertains to make and use the same.

My invention has for its object to provide a simple and highly efficient platen press gage; and to such ends, generally 15 stated, the invention consists of the novel devices and combinations of devices herein-after described and defined in the claims.

It is a well known custom in platen presses to cover the platen with a heavy 20 tough piece of paper known as a tympan or tympan paper and which is securely fastened to the platen by well known means. Hitherto, it has been the practice to apply 25 quads to the tympan to position the sheet of paper, card, envelop, or other article that is to receive the print. In practice, it has been found that these quads are liable to be 30 ripped off or to work out of position, and moreover, it is not an easy matter to position them so that they will accurately locate or efficiently hold the article while it is being printed.

My invention provides mechanical gages which are adapted to be very quickly and 35 accurately applied to the tympan sheet, and properly adjusted so that they will accurately position and securely hold the sheet or other article to receive the print.

The preferred form of the improved gage 40 is illustrated in the accompanying drawings wherein like characters indicate like parts throughout the several views.

Referring to the drawings,

Figure 1 is a side elevation of the gage; 45 Fig. 2 is a plan view thereof;

Fig. 3 is an end elevation of the gage looking at the same from the left toward the right, in respect to Fig. 2;

Fig. 4 is a bottom plan view of the front 50 end or the left hand portion of the gage, as shown in Fig. 2, some parts being broken away;

Fig. 5 is a section on the line 5—5 of Fig. 2 showing the gage applied to the tympan 55 sheet;

Fig. 6 is a transverse vertical section taken on the line 6—6 of Fig. 5; and

Fig. 7 is a small diagrammatic view illustrating the proper arrangement of a number of gages on the tympan sheet.

60

The clamp is made up of base and top members 8 and 9 of plate-like form having, respectively, overlapped hinge ears 10 and 11 at their intermediate portions connected by a hinge pin 11^a. The lower plate 8 is of 65 rectangular form while the upper plate 9, preferably, has its rear corners cut away, as best shown in Fig. 2, and at its front edge, it is provided with a downwardly projected clamping flange 12 that extends along 70 the front edge of the lower plate and has downwardly turned end extensions 12^a that extend short distances along the side edges of said lower plate.

Downward movement of the front edge 75 of the top plate 9 is limited to stop lugs 13 shown as formed as integral extensions of the hinge ears 10. A clamping screw 14 works freely through a perforation in the central front portion of the top plate 80

9 and has threaded engagement with the clamping bar 15 that is located just inward of the clamping flange 12. Working with threaded engagement through the central rear portion of the top plate 9 is a longer 85 clamping screw 16, the lower end of which bears against the rear portion of the bottom plate 8. The numeral 17 indicates a so-called fender which is preferably made of so-called stitching wire and is capable of 90 being formed into position, but which will, nevertheless, maintain its shape against light pressure, such as required to hold a sheet, or the like, in position for printing.

This wire fender is bent into a yoke-like 95 form and its legs are passed through small perforations 18 in the clamping flange 12 and thence upward and rearward over the top of the clamping bar 15. When the screw 14 is tightened, the clamping bar 15 100

will pinch the wire fender and hold the same in whatever position of projection it may be set. The projecting loop of the fender may then be bent so that it will be the desired distance from the tympan. 105

In Fig. 7 the platen is indicated by the numeral 19 and the tympan sheet by the numeral 20. This view also illustrates the manner in which three of the fenders will be located to hold in position a sheet 21, 110

which latter is indicated by dotted lines in Fig. 7. The tympan sheet 20 is also illustrated in Fig. 5. Here it will be noted that the gage is adapted to be anchored to this sheet by providing the sheet with a slit through which the front edge of the bottom plate 8 may be passed, as shown in said Fig. 5. When the screw 16 is then tightened, the lower edge of the clamping flange 10 12 will be caused to pinch the upturned portion of the tympan sheet between the same and the front edge of the bottom plate 8, thereby securely anchoring the gage in position. Obviously, before the gage is thus secured to the tympan sheet it may be accurately adjusted so as to give, when desired, a "hair line registration" of the sheets that are to be printed and that are to be positioned by the several gages.

20 Obviously, the gage described, while of the simple construction is strong and durable and has no parts that can get out of place or that may be broken even under rough handling. Also it is obvious that it is an 25 easy matter to accurately apply the gages in position on the tympan sheet and to remove the same. The gage is always ready for use. The fender is a permanent part of the gage and because of its simplicity and 30 adjustability, may be very easily set for holding various different kinds of work, such as paper sheets, envelopes, articles to be embossed. The fender can be bent down, so that it will either lie very close to the 35 tympan sheet when desired, or it can be bent up to adapt the gage to hold thereon articles to be printed. In the use of these improved gages, the stock can be fed more regular, faster and with less tripping of 40 the press and less waste of the stock than with any of the devices hitherto used for the same purpose, and it is free from the various objectionable fitting of such prior devices.

45 What I claim is:

1. A press gage comprising a bottom plate having upturned hinge ears, a top plate having downturned hinge ears pivotally connected to the hinge ears of said bottom plate, said top plate, at its front edge having a depending clamping flange that overlaps the front edge of said bottom plate to clamp an interposed portion of a tympan sheet, the said depending clamping flange 50 having back turned end portions that co-operate with the front side edges of said bottom plate to increase the clamping action on the tympan sheet.

2. A press gage comprising a bottom 60 plate having upturned hinge ears, a top plate having downturned hinge ears pivot-

ally connected to the hinge ears of said bottom plate, said top plate, at its front edge having a depending clamping flange that co-operates with the front edge of said bottom plate to clamp an interposed portion of a tympan sheet, a clamping bar adjustably applied to the underside of said top plate adjacent to its depending clamping flange, and a pliable wire fender passed through 65 perforations in said clamping flange and passed between said clamping bar and said top plate, the ears of said bottom plate having projecting stop lugs that limit the downward movement of the front portion of said 70 stop plate.

3. A press gage comprising pivotally connected top and bottom plates having co-operating tympan clamping edges and means for adjusting said plates to cause 80 the same to clamp the gage onto a tympan sheet, a fender made of pliable material and adapted to be bent to different forms and to maintain any form into which it is bent, and an adjustable clamp for adjustably securing the fender to one of said plates.

4. A press gage comprising pivotally connected top and bottom plates having tympan clamping edges and means for adjusting the plates to cause the same to clamp the 90 gage onto a tympan sheet, of an approximately U-shaped pliable wire-like fender, the legs of which are adjustably secured to said upper plate, said fender being adapted to be bent into different forms and to maintain any form into which it is bent.

5. A press gage comprising pivotally connected top and bottom plates, the former of which has at its front edge a depending flange that extends forward of the front edge of the bottom plate for co-operation therewith to clamp an interposed portion of a tympan sheet, and an adjusting device for the top plate.

6. A press gage comprising pivotally connected top and bottom plates, the former of which has at its front edge a depending flange that extends forward of the front edge of the bottom plate for co-operation therewith to clamp an interposed portion of a tympan sheet, an adjusting device for the top plate, 105 a fender extending through apertures in the clamping flange, and a clamping device for securing the fender in respect to the top plate.

110 In testimony whereof I affix my signature in presence of two witnesses.

WILLIAM H. BOSEN.
